METHOD OF COLLECTING AND CONDENSING A MEDICAL SPECIMEN

James B. McCormick, La Grange, Ill., assignor, by mesne assignments, to Ames Lab-Tek, Inc., a corporation of Massachusetts

Filed Apr. 15, 1963, Ser. No. 273,093
1 Claim. (Cl. 233—26)

This invention relates to the collection of specimens of pathologic material to be used for bacteriologic examinations and, more particularly, to receptacles utilized to collect specimens of sputum for such examination.

In order to diagnose the presence in the body of certain disease-producing bacteria or the presence of cells indicating the presence of a disease, a physician will frequently request that a specimen of the sputum of the patient be obtained and analyzed. Sputum consists of secretory material from the lower respiratory tract and is preferably collected soon after the patient awakes in the morning by expectoration by the patient into a receptacle. The specimen is then analyzed and its volume, odor, color, and cellular and bacteria content noted. Normally, the notation of the cellular and bacteria content includes a microscopic examination of the specimen and, frequently, the preparation of cultures therefrom. Both of these latter procedures make it desirable to centrifuge the specimen to concentrate and separate the sputum from saliva and nasopharyngeal secretion.

The conventional procedure for obtaining and analyzing sputum specimens is not entirely satisfactory. Normally, sputum is collected from the patient in a glass dish, paper cup, or other receptacle which, because of its open construction, makes it easier for the patient to deposit the specimen therein. Such a receptacle is generally not suitable for use in an analysis of the specimen, however, or even the storage thereof for an extended period of time.

On the other hand, laboratory apparatus such as is used in an analysis of the specimen is generally not suitable for the collection of the specimen from the patient because its size would frequently make it difficult for the patient to deposit the specimen in it, and also because of the susceptibility of the apparatus to breakage and the general instability of the apparatus which would render it difficult for the patient to handle unassisted. Hence, after the specimen has been obtained, it must be transferred to a test tube or similar piece of laboratory apparatus from which the analysis can be performed. In the course of the analysis, several transfers to various forms of apparatus are not uncommon. Occasionally, the specimen is shipped to a distant laboratory for analysis, in which case the receptacle to which the specimen is transferred must be one which is capable of withstanding the stresses which arise during shipment.

Also, since the specimen is preferably obtained from the patient soon after the patient awakes, the receptacle in which it is received should preferably be left overnight with the patient, as on a bedside table. However, many receptacles conveniently used for this purpose are relatively unstable and are prone to be easily upset either prior to, or after, the specimen has been deposited therein. Other receptacles are of such dimensions that a patient, particularly a semi-invalid, has difficulty in depositing the specimen therein. Further, the dish-shaped receptacles which provide a wide area for the receipt of the specimen possess the disadvantage of not including a lid. Such receptacles are difficult to maintain in a sterile condition prior to the introduction of the specimen, and create the possibility of the specimen being spilled from the receptacle while it is being collected.

2

When a paper receptacle is used, it is difficult to insure its initial sterility and, if the outside of the receptacle becomes contaminated while the specimen is being deposited therein, it is not possible to readily decontaminate the receptacle for the benefit of those who must handle it.

Moreover, as previously mentioned, the specimen is generally centrifuged prior to the microscopic examination thereof and the preparation of culture therefrom.

10 After decantation, the remaining concentrate is quite tacky and tenacious and its removal from the centrifuge tube is difficult.

Accordingly, the principal object of the present invention is to provide an improved receptacle for the collection of sputum.

15 Another object of the invention is to provide such a receptacle which can be easily maintained in a sterile condition and which is particularly adapted to be utilized by the patient without assistance.

20 A further object of the invention is to provide an improved receptacle which is adapted to be utilized for the collection of a sputum specimen from a patient, for the centrifugation of the specimen, and which is adapted to facilitate the transfer of a portion of the specimen to a slide.

25 A still further object of the invention is to provide an improved disposable receptacle for the collection of sputum, which receptacle is economical to produce, convenient to use, and is adapted for the storage and shipment of the sputum as well as the collection thereof.

30 Other objects and advantages of the invention will become apparent with reference to the following description and the accompanying drawing.

In the drawing:

40 FIGURE 1 is a perspective view of a device showing various of the features of the invention;

FIGURE 2 is an enlarged exploded elevational view of the device of FIGURE 1;

45 FIGURE 3 is an enlarged elevational view, partially in section, of a portion of the device of FIGURES 1 and 2; and

50 FIGURE 4 is a perspective view on a reduced scale showing a manner in which the sputum can be transferred from a portion of the device of FIGURES 1 through 3 to a microscopic slide.

55 Very generally, in the illustrated embodiment of the invention, a device 11 is provided and comprises a hollow tubular receptacle 13 maintained in generally upright disposition by a stand or base 15. The upper end of the receptacle defines a wide mouth 17 through which the sputum is deposited, and a cap 19 is provided which serves as a closure for the mouth. The lower end 21 of the receptacle is closed and is formed so as to taper inwardly and downwardly, and the walls of the tapered lower portion 21 are provided with lines of weakness 23 to permit a lower section thereof to be separated from the remainder of the receptacle so as to thereby facilitate the removal of material through the lower end of the receptacle.

60 65 More particularly, the receptacle 13 is preferably fabricated of an inexpensive material so that it can be produced with a minimum of expense and thus discarded after a single use. The material of which the receptacle is fabricated should also be such as will permit a lower section of the lower tapered portion 21 to be easily separated from the remainder of the receptacle, as along a line of weakness 23. Hence, the material should be

susceptible to fracture or severance along a fairly well-defined plane. Furthermore, the material is preferably flexible and deformable so as to permit the wall of the receptacle defining the mouth 17 to conform to the mouth of the patient, and also to permit the transfer of the material contained in the receptacle to a slide by the collapsing of the separated lower section of the tube. A material which is satisfactory in all of the above respects is a flexible thermoplastic material such as polyethylene having an average thickness at the walls of the tube of about one millimeter.

The central portion of the receptacle is of a generally cylindrical tubular construction and includes an upper cylindrical section 25, and a lower cylindrical section 27 having an outer diameter slightly less than that of the upper section. The lower edge of the wall of the upper cylinder therefore projects outwardly from the outer surface of the wall of the lower cylinder and defines a downwardly facing ledge 29 which is engageable with a shoulder 31 of the stand 15 so as to position the receptacle thereon, as hereinafter described. The cylindrical configuration of the central portion of the receptacle renders the receptacle particularly adapted to be carried within a centrifuge, thus rendering it useful both in the collection of the sputum and in the laboratory analysis thereof.

The upper cylinder is flared adjacent its upper end to define the wide mouth 17, the diameter of the mouth being preferably of the order of 4 centimeters so as to accommodate the puckered lip portion of the mouth of the expectorating patient. In this respect, the angle of the flared portion of the mouth-defining wall preferably closely approximates the inclination of the lips of such a patient. When the receptacle is formed of a flexible material, the rim 33 of the mouth of the receptacle is capable of being accommodated to the contours of the mouth of the patient, thereby facilitating the deposit of sputum in the receptacle by the patient.

The rim 33 is generally cylindrical and an inwardly directed lip 35 adjacent its upper edge serves to retain the cap 19 in place, as hereinafter described.

The cap 19 comprises generally a flat circular plate 37 having a depending flange 39 disposed normal to the plane of the plate and offset slightly from its periphery. The outer upper surface of the flange is inclined for a portion of its length and terminates in a downwardly facing shoulder 41 which engages the upper edge of the rim 33 when the cap is in place. A groove 43 is provided in the outer surface of the flange immediately below the shoulder to receive the lip 35, and the lower outer edge of the flange is chamfered, as at 45, to enable it to be cammed over the lip 35 and into a position in which the lip occupies the groove 43 of the flange.

The interengagement between the flange 39 of the cap 19 and the rim 33 provides an essentially fluid-tight seal between the cap and body of the receptacle which prevents the specimen from being lost if the receptacle should be upset but, more importantly, permits the receptacle to be used for the shipment of the specimen.

The cap 19 is hingedly attached to the tubular body of the receptacle by a flat strip 47 of flexible material which is connected at one of its ends to the upper portion of the tubular body of the receptacle, and at the other of its ends to a peripheral portion of the cap. The hinge permits the cap to be moved to an out-of-the-way position while the patient is depositing the specimen therein, but allows the cap to remain attached to the receptacle so that it will not be lost or misplaced. A finger tab 49 is provided on the cap opposite the hinge 47 to facilitate the displacement of the cap to an open position.

The lower end 21 of the tubular body is normally closed and is formed so as to taper sharply and irregularly to a blunt point, thereby rendering the lower end of the tube of a narrower diameter. When the sputum is deposited in the receptacle, it is generally accompanied by a quan-

10 tity of saliva from which it is later separated by centrifugation. The tapering of the lower ends of the receptacle causes the sputum to occupy a relatively greater depth than would be the case if the receptacle were of the same diameter throughout its length, and thus renders the specimen easier to decant than if the sputum formed only a thin layer. Moreover, when the relatively heavy specimen is deposited in the tapered lower portion, it lowers the center of gravity of the receptacle and thus renders it more stable and less susceptible to being upset.

15 More specifically, the tapered lower end 21 of the tube comprises essentially three sections 51, 53 and 55. The wall defining the uppermost section 51 is inclined inwardly relatively sharply and extends downwardly from the lower edge of the cylindrical body approximately one-third the length of the tapered lower portion. The wall is notched slightly as at 57 adjacent the lower edge of the upper section to provide a line of weakness 23a, which line of weakness encircles the tapered lower portion and defines a plane along which the sections 53 and 55 of the tapered portion can be separated from the remainder of the receptacle in a manner hereinafter described.

20 Depending from the walls of the notch 57 is a generally vertically disposed skirt portion 59 of relatively brief length, and the intermediate tapered section 53 depends from the lower edge of the skirt 59, the walls of the intermediate section 53 being inclined at somewhat less of an angle than the inclination of the walls of the upper section 51. A notch 61 defining a line of weakness 23b is provided adjacent the lower end of the intermediate section and encircles the lower tubular section to define a second plane along which the section 55 of the lower tubular portion may be separated from the remainder of the receptacle.

25 A generally vertically disposed skirt 63 depends from the notch 61, and the third or end section 55 is attached to the lower edge of the skirt, the walls of the third section being inclined at substantially the same angle as the walls of the intermediate section 53. The wall of the lower section tapers to a blunt point to close the body at its lower end.

30 The stand 15 maintains the receptacle in a stable generally upright position as, for example, on a table adjacent the bedside of a patient or on a laboratory table, but also may be utilized in the handling of the receptacle, as will be discussed shortly. The stand is preferably made of a durable material such as metal so that it can be sterilized and reused, but may, if desired, be formed of a paper or cardboard and thus rendered disposable.

35 More specifically, the stand includes a hollow base having a central section 65 in the form of an inverted truncated cone. A flange 67 depends from the lower edge of the cone to a surface-engaging position, and a second flange 69 extends upwardly from the upper edge of the cone to receive a sleeve 71, hereinafter described. The diameter of the lower edge of the base, as defined by the lower flange, is sufficiently great to render the stand and receptacle supported therein stable under normal conditions.

40 The sleeve 71 is carried by the base and includes a generally cylindrical side wall defining a lower section 73 closed at its lower end, and an upper section 75 of slightly greater outer diameter than the lower section. The juncture of the two sections defines a downwardly facing ledge 77 which engages a shoulder 79 defined by the upper edge of the upper flange of the base, thereby positioning the sleeve on the base. The upper edge of the upper cylindrical section 75 defines the shoulder 31, previously referred to, which is engaged by the ledge 29 of the receptacle. The body, sleeve and base thus telescope inside one another, and their relative positions are determined by the interengagement of the ledges 29 and 75 and shoulders 31 and 79.

In the use of the device 11, the disposable receptacle 13 is preferably placed in a sterilized condition in a stand 15, also preferably sterilized. The device is then placed upon the bedside table of the patient in the evening with instructions to the patient to deposit a specimen of sputum in the receptacle shortly after he awakes in the morning. This can therefore be accomplished by the patient without the assistance of a nurse or attendant by merely placing the receptacle with the flared mouth 17 thereof in surrounding relation to his lips and expectorating into the receptacle.

After the patient has deposited the specimen, the nurse removes the receptacle and delivers it to the laboratory for analysis. Occasionally, part of the specimen, particularly salivary material, is deposited on, and contaminates, the side walls of the receptacle. In such a case, the nurse may handle the receptacle by means of the stand 15.

In the laboratory, the volume, odor and color of the specimen are noted and certain preliminary tests may be made thereon as required. The receptacle is then removed from the stand and placed in a centrifuge. When the tube is removed from the centrifuge, the material is decanted, thus separating the concentrate from the liquor, i.e., the saliva and other lighter materials.

In order to remove the concentrate from the lower portion 21 of the receptacle, a lower section of the lower portion is separated from the remainder of the receptacle, as along a line of weakness 23, thereby providing a conical-shaped cup (FIG. 4) in which the concentrate is carried. The concentrate may be easily removed from this cup by merely collapsing the cup between the thumb and forefinger while spreading the concentrate onto a microscope slide.

The receptacle described is thus adapted to be used for the collection of a sputum specimen from a patient, and for the laboratory analysis of the specimen including the centrifugation thereof. Moreover, when the centrifuging has been completed, the receptacle is particularly adapted to the transfer of the tenacious, tacky concentrate from the receptacle to a slide by the provision of lines of weakness in the lower portion of the receptacle which makes it possible to separate a segment of the receptacle containing the concentrate from the remainder of the receptacle, from which segment the concentrate can be easily removed.

While various of the structural features of one specific embodiment of the invention have been shown and described, it should be apparent that various modifications may be made therein without departing from the scope of the invention.

What is claimed:

A method of collecting and condensing a specimen of sputum from a patient comprising

(A) providing the patient with a sputum receptacle formed to provide

(1) a tubular main body portion,

(2) and a lower fall portion integral with the main body portion and of tapered configuration so as to define a hollow tip at the lower end of the receptacle,

(a) said receptacle being formed of a flexible material so as to render said tip easily collapsible when detached from said intermediate wall portion,

(B) collecting a specimen of sputum in the receptacle,

(C) centrifuging the specimen in the receptacle to cause a condensate to accumulate in the hollow tip at the lower end of the receptacle,

(D) decanting the liquor from the condensate while causing the condensate to remain in the hollow tip,

(E) severing the hollow tip from the remainder of the receptacle by rupturing the wall thereof,

(F) and transferring the condensate from the tip onto a slide for microscopic examination by collapsing the hollow tip so as to cause the condensate to be discharged therefrom.
